UNITED STATES PATENT OFFICE.

CHARLES A. HONSINGER, OF DETROIT, MICHIGAN.

BANK SAFETY DEVICE.

Application filed February 9, 1920. Serial No. 357,191.

To all whom it may concern:

Be it known that I, CHARLES A. HONSINGER, a citizen of the United States of America, residing at Detroit, in the county of Wayne and State of Michigan, have invented certain new and useful Improvements in Bank Safety Devices, of which the following is a specification, reference being had therein to the accompanying drawings.

This invention relates to window and counter construction for banking institutions and such places where money and valuables are handed back and forth from one side of the counter to the other. Such institutions are often robbed and moneys procured from under the windows, the robbers escaping before the cashier or teller can send in an alarm.

The main object of my invention is to provide a bullet proof window or partition with novel coin ways which will permit of coins, bills and other papers being passed back and forth, without any danger of moneys being unlawfully obtained by a person outside of the windows slipping the hand under the window without detection.

Another object of my invention is to provide a counter and wicket construction which will prevent robbers from placing a gun under the wicket and aiming the same.

A further object of my invention is to provide a window and counter construction for banks which will present a neat appearance, not interfere with usual banking operations, and at the same time afford a degree of safety for the employees of a bank.

The above and other objects are obtained by a mechanical construction that will be hereinafter considered and then claimed, and reference will now be had to the drawing, wherein—

Figure 1 is a perspective view of a window and counter provided with deal boxes.

Figure 2 is a cross sectional view of a portion of the counter having deal passages, and

Figure 3 is a perspective view showing a modification.

Considering Figures 1 and 2, the counter 1 is provided with a suitable partition 2 made of heavy plate glass, wire glass and metal, or any material which will retard or deflect a bullet. The partition has a window 3 and above the window is a bullet proof panel 4, which may be located at any desired point (Figure 1 showing it in one

location and Figures 2 and 3 showing it in a different location) and which may be arranged so that it can be swung inwardly to an open position when it is desired to pass 60 bulky matter over the counter; otherwise the panel 4 is locked so as to protect the cashier, teller or clerk behind the counter.

Mounted on the counter 1, in the window 3, are deal boxes 5 and 6, one being the reverse of the other so that money may be passed back and forth through the window. The deal boxes are identical in construction and are placed side by side with a partition 7 common to both boxes. The box 5 provides an inclined way 8 which has its upper edge in a plane with the upper edge of the panel 4, as best shown in Figure 2, so that it will not be easy for a person outside of the window to insert a gun in the passage 75 way 8 and aim the gun at a person behind the counter. The arrangement of the passage ways are such as not to interfere with the deposit of money in the upper ends 70 thereof, and the money will readily slide 80 under the window to a place convenient to the cashier.

Considering the box 6, it will be noted that this box presents an abrupt shoulder 85 right inside of the window which will interfere with the aiming of a gun barrel or the turning of a hand or arm under the window for aiming purposes. The box will permit of the cashier dropping money under the window so that it will slide outwardly to a 90 customer at the outer side of the counter.

Instead of attaching the deal boxes for the counter, as in Fig. 1, I may form a counter 9 with parallel deal passages 10, and the protecting panel or partition 4 may have 95 its lower edge countersunk in the counter. The deal passages will be restricted by the lower edge of the panel to such an extent that a gun barrel cannot be successfully aimed or manipulated in the passage 8 to 100 cause any uneasiness of a cashier or clerk behind a counter.

It is thought that the utility of my invention will be apparent without further description, and while in the drawing there are illustrated the preferred embodiments of my invention, it is to be understood that the construction is susceptible to such changes as fall within the scope of the appended 105 claim.

What I claim is:—
In a structure for the protection of

tellers, a counter, a partition thereabove between teller and customer, a vertically-extending member positioned relative to the counter to provide a space for the passage of funds, etc., means operative to set up "one-way passage" conditions in opposite directions within such space, said means including a passageway formation having its exit end on the customer side of the member, the portion of the passageway on the opposite or entrance side of the member having its bottom wall contour curved upwardly, the plane of the entrance end of such passageway being above the bottom of the

vertically-extending member, the curvature 1 of the upwardly-curved wall and the distance between the wall and the vertically-extending member on the plane of the entrance end of the passageway being such that unimpeded discharge of a fire arm in 20 said passageway is limited to a generally vertical direction.

In testimony whereof I affix my signature in the presence of two witnesses.

CHARLES A. HONSINGER.
